CLAYTON LAING, OF CHICAGO, ILLINOIS.

BLOWPIPE.

1,379,708.

Specification of Letters Patent. Patented May 31, 1921.

Application filed May 24, 1918. Serial No. 236,390.

To all whom it may concern:

Be it known that I, CLAYTON LAING, a subject of the King of Great Britain, residing at Chicago, in the county of Cook and 5 State of Illinois, have invented certain new and useful Improvements in Blowpipes, of which the following is a specification.

My invention relates to a blow pipe or torch, and more particularly to a device of 10 this sort for use by dentists, jewelers or other metal workers for soldering, welding and other like operations.

A blow pipe of the type which my invention seeks more particularly to improve 15 upon, employs gas as a fuel and is used in connection with a supply of compressed air delivered to the point of combustion of the gas. It has been proposed to provide a blow pipe of this sort with separate control valves 20 for the gas and air conduits by means of which the volume of flame and also its character may be varied by increasing or decreasing the amounts of gas and air delivered to the combustion point, changing when 25 necessary the ratio of air to gas. But the inconvenience of having two valves to control, especially the loss of time in making adjustments necessary to obtain the proper 30 quantities of the fluids at the right proportions for the particular operation and the liability of having the flame blown out by excess of air make this arrangement quite 35 impractical for some kinds of work. Blow pipes have also been used having gas and air 40 valves geared or otherwise connected together for operation in synchronism, that is to say, for the purpose of increasing and decreasing the air proportioned with the increase and decrease of the gas flow. But 45 this arrangement gives no opportunity for changing at will the ratio between air and gas to vary the character of the flame; and this is very desirable, and, in fact, necessary, 50 for certain operations. For this and other 55 reasons manually governed blow pipes utilizing compressed air have not come into very general use. Jewelers, for example, still employ, ordinarily, the mouth blow pipe which, although its use involves many 55 inconveniences, is capable of a delicacy of control possessed, so far as I am aware, by no blow pipe having manual control which has been produced prior to my invention.

One of the objects of my invention is to 55 provide controlling means for a blow pipe, torch or other like instrument, whereby,

through the movements of a single controlling element adapted to be moved by the thumb of the operator, for example, the increase or diminution of gas supplied to the 60 point of combustion will be accompanied by an increase or diminution of the air, but at a ratio, as between air and gas, which may be varied at the will of the operator, so that the single controlling element governs both 65 the volume of the flame and also its character which is dependent on the proportion maintained between the fluids.

A further object of the invention is to provide an arrangement whereby the shut-off or diminution of the flow of air through the instrument does not involve any excessive pressure back of the point where the shut off takes place; this result being accomplished by providing an exhaust port controlled in synchronism with the air port or ports to which the air passes to the combustion point, so that said exhaust port is opened when said air port or ports are closed and closed when the same are opened. 70 In a blow pipe the gas receiving pipe and the air receiving pipe are connected by flexible tubing with their respective supply lines. In operation the valve at the gas supply line is opened and, with both air and 75 gas valves in the blow pipe opened, enough air is turned on from the valves in the air supply line to produce the maximum blast flame. In the ordinary blow pipe, as soon as the flow of air is substantially diminished or cut off, the air pressure back of the valve in the blow pipe approximates or equals that 80 within the supply line or tank. This equalization of pressure under these circumstances may involve the blowing off of the connecting tube if the supply pressure is high and, 85 in any event, under such pressure it is difficult to control the air for the finer and more delicate flames. Again, if it were possible to so construct a blow pipe and connecting tube to withstand this pressure, if 90 the gas and air valves were operable in synchronism and proportioned to operate from an air supply of one pressure they would not do so when attached to a supply 95 of a different pressure.

It will be apparent that the two improvements outlined above, which constitute the primary objects of my invention, are susceptible of use singly as well as conjointly; 110 although to get the best results both expedients must be employed. When both are

used, in the manner to be hereinafter described, a blow pipe is provided having a manual air control which is delicate and accurate enough so that the instrument may 5 be used on operations that ordinarily have necessitated the use of the mouth blow pipe. In soldering and welding operations involving small pieces of metal which have to be accurately placed the operator has one hand 10 engaged holding soldering pliers or the like and ordinarily the melting operations must be performed with rapidity. Where such operations necessitate changes in the character of the flame such changes must be 15 brought about very expeditiously and by movements which can be executed more or less automatically or subconsciously. The device of my invention meets these requirements fully.

20 The invention is illustrated, in a preferred embodiment, in the accompanying drawing wherein—

Figure 1 is a longitudinal sectional view of a blow pipe constructed in accordance 25 with the invention.

Fig. 2 is a plan view of the same.

Fig. 3 is a vertical sectional view on line 3—3 of Fig. 1.

Fig. 4 is a sectional plan on line 4—4 of

30 Fig. 3.

Fig. 5 is a diagrammatic view showing the relation of the several coöperating ducts and ports in the control valve and valve casting, the rectangular figure representing a 35 development of the valve casing as the casting would appear if it were severed on a longitudinal line at the bottom of the casing and flattened out, and

Fig. 6 is a view, in perspective, of the 40 controlling valve.

Like characters of reference designate like parts in the several figures of the drawing.

Referring to the drawing, A is a gas receiving pipe adapted to be connected, for 45 example, by a rubber hose A' with a supply of gas, B an air receiving pipe similarly connected by hose B' with a supply of compressed air. C is a gas delivery pipe, D the air delivery pipe located within pipe C, E a tubular member forming a casing for the 50 cylindrical control valve F, and G an exhaust pipe which is arranged between pipes A and B; pipes A, B and G being preferably bent to form a handle for the instrument.

55 Pipe A is divided by a partition 10 (Fig. 4) to provide what might be termed an inlet chamber designated 11, and an outlet chamber designated 12, the pipe and valve casing E being provided with inlet and outlet ports 13 and 14 on opposite sides of partition 10, and pipes A and C with a port 15.

60 A partition 16 divides air pipe B into the inlet chamber 17 and outlet chamber 18. A 65 port 19 leads from chamber 17 to the valve

chamber E and a port 20 from the valve chamber to chamber 18. Arranged within the inner portion of gas pipe C against the end of air pipe D is a partition 21, this partition being formed with a port 22 and 70 a port 23 being provided between the air outlet chamber 18 and the space 24 at the inner end of pipe C whereby air from pipe B after passing the valve F, as will be hereinafter described, will enter the air de- 75 livery pipe D.

The valve F is preferably a solid cylindrical member arranged in the valve casing E so that it may be moved longitudinally thereof and also rotated therein to the extent permitted by the slot 25 formed in the top of the valve casing through which projects a stud 26 provided with a button or knob 27 for the thumb of the operator. The valve is formed with a longitudinal groove 28 preferably of the same width and depth for the major part of its length but tapered at one extremity as indicated at 29 (see Figs. 4 and 5). In the retracted position of the valve, the position shown in the drawings, the tapered end 29 of duct 28 overlaps slightly the gas outlet port 14. In all positions of the valve duct 28 is in communication with the gas inlet port 13. In the position of the valve shown enough gas will be 80 delivered to the combustion point of the blow pipe, that is, to the opening 30 in the end of pipe C to maintain a pilot flame. As the valve is moved forward the effective opening between the gas duct and the gas 85 outlet port 14 is increased, thereby increasing the volume of gas flowing through the instrument. It will be observed that a 90 movement of rotation of the valve has no 95 effect upon the gas flow.

100 The valve is provided on the side opposite gas duct 28 with an air duct 31 tapered at one end, as shown at 32. In the retracted position of the valve the air duct 31 lies across the air inlet port 19 but does not 105 communicate with the air outlet port 20. In other words, the air is shut off in this position of the valve. As the valve is moved forward, that is to say, longitudinally in the casing E, the pointed end 32 of the duct 110 31 intersects the air outlet port 20 providing an orifice for the outflow of the air which increases with the forward movement of the valve. Considering only the longitudinal 115 movement of the valve, that is, assuming that when it is moved forward it is not rotated, the amount of air delivered to the combustion point has a fixed relation to the amount of gas for any position of the valve. Preferably the ducts are so designed as to 120 make this relationship a constant ratio. To vary this ratio, that is, to increase or decrease the proportion of air to gas, the button 27 is moved laterally which gives a 125 movement of rotation to the valve. In prac- 130

tice the valve may, of course, be rotated and moved longitudinally at the same time. The rotation of the valve, as has been stated, does not, in the preferred arrangement of 5 the ports shown, affect the flow of gas; but so far as the air is concerned, it brings about a diminution or increase of the effective size of the controlled air orifice due to the fact that the edge 33 of the air duct 20 10 which is intersected by the tapered end 32 of duct 31 is oblique to the axis of the duct instead of being at right angles thereto as in the case of the gas outlet 14. By these arrangements the flow of air through the instrument is synchronized with the flow of 15 gas, the increase of flow of gas involving an increased flow of air, and vice versa, but the ratio between gas and air may be varied at the will of the operator. While it is desirable to have the gas vary only with the 20 longitudinal movement of the valve and the air vary both with longitudinal movement and the rotation of the valve, as shown, this is not the only arrangement possible. The 25 gas might be cut off on rotation of the valve while the air flow remained constant, or both air and gas might be varied at both movements of the valve.

The other feature of my invention, the arrangements whereby undue air pressure in the instrument is prevented when the flow of air therethrough is diminished, will next be described. The desired result is accomplished by providing a controllable air exhaust port, the control of which is synchronized with the control of the air passing to the combustion point so that when the flow of air through the air delivery pipe is cut off or diminished the exhaust orifice is 30 opened to the extent required to prevent accumulation of pressure. With this object in view the air duct 31 is formed with a branch 34 leading to a tapered duct 35 which intersects an air exhaust port 36 that 35 is conformable to the controlled air port 20 but oppositely disposed with respect thereto. The port 36 is arranged in the bottom of the valve chamber (Fig. 1) and communicates 40 with an opening in the exhaust pipe G. 45 The exhaust pipe might be dispensed with. Its purpose is simply to carry the exhaust to a convenient point away from the work. The exhaust pipe is formed at its lower extremity with a perforation 37. It will be understood that the dimensions of the several ports of the air system are calculated, with respect to the resistance to the air flow presented by the conduits or series of passageways and orifices through which the air must pass to the point of combustion and to the exhaust opening so that the movement of the valve F, either forwardly, backwardly or rotationally, will not involve any accumulation of pressure in any part of the air system. When the valve is moved

forwardly the effective size of the orifice provided by the outlet port 20 and the tapered end 32 of the air duct is increased. At the same time the effective size of the corresponding orifice provided by the tapered end 35 of the duct and the air exhaust opening 36 is proportionately decreased. Corresponding proportional increase and decrease in the sizes of these openings is brought about by the rotation of 70 the valve. The drawing, it will be understood, illustrates only approximately the proper dimensions of the several air ports and passageways, this matter being one of suitable mechanical design. 75

While I have described my invention in a preferred embodiment, it will be understood that there may be considerable modification in the mechanical structure disclosed without departure from the principles of the 80 invention. Therefore I do not wish to be understood as limiting the invention to the arrangements, constructions and devices shown and described except so far as the 85 claims hereto appended may be specifically so limited.

I claim:

1. In a blow pipe, governing means for the gas and air comprising a single controlling element by the movements of which the flow 95 of gas and air may be increased or decreased synchronously in proportions variable at will.

2. In a blow pipe, governing means for the air and gas comprising a single controlling 100 element having two ranges of movement, one effecting the increase and decrease of gas flow to the combustion point and, synchronously therewith, the increase and decrease of air thereto, the other bringing about a variation in the proportions of air and gas. 105

3. In a blow pipe, governing means for the gas and air comprising a single controlling element longitudinally movable to vary the flow of gas to the combustion point and, 110 synchronously therewith, the flow of air thereto, and rotatable to vary the proportions of air and gas.

4. The combination with a blow pipe having a nozzle, of means for supplying air and 115 gas thereto, and controlling means comprising a single controlling element for increasing and decreasing the flow of air and gases through said nozzle synchronously and in proportions variable at will. 120

5. In a blow pipe, the combination of gas and air receiving and delivery pipes, a valve casing and a valve movable longitudinally and rotatably in said casing, said pipes, casing and valve being provided with gas and 125 air ports arranged so that the longitudinal movement of the valve increases or decreases, according to the direction of said movement, the flow of gas and air to said delivery pipes, respectively, while the rota- 130

- tion of the valve increases or decreases, according to the direction thereof, the flow of air without affecting the flow of gas.
6. In a blow pipe, the combination of gas and air receiving and delivery pipes, a valve casing formed with a slot and a valve in said casing longitudinally movable and rotatable therein and provided with a manipulating element projecting through said slot, said pipes, casing and valve being provided with gas and air ports arranged so that the longitudinal movement of the valve increases or decreases, according to the direction of said movement, the flow of gas and air to said delivery pipes, respectively, while the rotation of the valve increases or decreases, according to the direction thereof, the flow of air without affecting the flow of gas.
7. The combination with a blow pipe, of gas receiving and delivery pipes having gas inlet and outlet ports, respectively, associated therewith, air-receiving and delivery pipes having air inlet and outlet ports, respectively, associated therewith, and controlling means comprising a single controlling element for said gas and air ports for increasing or decreasing the flow of air and gas synchronously and in proportions variable at will.
8. In a blow pipe, the combination of gas receiving and delivery pipes, air receiving and delivery pipes, a valve casing having gas inlet and outlet ports communicating with said gas receiving and delivery pipes, respectively, and air inlet and outlet ports communicating with said air receiving and delivery pipes, respectively, and a valve slideable in said casing and capable of being held in any desired position by friction formed with a duct to put said gas inlet and outlet ports in communication with each other and with a duct to put said air inlet and outlet ports in communication with each other; the extremities of the ducts which coöperate with said outlet ports, respectively, being tapered, for the purpose described.
9. In a blow pipe, the combination of gas receiving and delivery pipes, air receiving and delivery pipes, a valve casing having gas inlet and outlet ports communicating with said gas receiving and delivery pipes, respectively, and air inlet and outlet ports communicating with said air delivery pipes respectively, and a valve slideable and rotatable in said casing formed with a duct to put said gas inlet and outlet ports into communication with each other and with a duct to put said air inlet and outlet ports into communication with each other; said ports and ducts being conformed so that the longitudinal movement of the valve in opposite directions increases and decreases the flow of gas and therewith the flow of air to the respective delivery pipes, while the rotation of the valve operates to vary the proportion of air and gas.
10. In a blow pipe, the combination of gas receiving and delivery pipes, air receiving and delivery pipes, a valve casing having gas inlet and outlet ports communicating with said gas receiving and delivery pipes, respectively, and air inlet and outlet ports communicating with said air delivery pipes, respectively, and a valve slideable and rotatable in said casing formed with a duct to put said gas inlet and outlet ports into communication with each other and with a duct to put said air inlet and outlet ports into communication with each other; the extremities of said ducts coöperating with said outlet ports, respectively, being tapered for the purpose described, and the edge of the gas outlet port intersected by the gas duct being at right angles to the axis of said duct while the edge of the air outlet port intersected by the air duct is oblique to the axis of said duct.
11. A blow pipe having an orifice through which air passes to the combustion point and an exhaust orifice, in combination with means for simultaneously controlling said orifices to maintain substantially uniform air pressure in the instrument.
12. A blow pipe having an orifice through which air passes to the combustion point and an exhaust orifice, in combination with means for simultaneously controlling said orifices comprising a single controllable element, the movement of which opens the exhaust orifice to the extent that the other orifice is closed, and vice versa, whereby substantially the same pressure is maintained in the instrument.
13. A blow pipe having an orifice through which air passes to the combustion point and an exhaust orifice, in combination with means for simultaneously controlling said orifices comprising a single valve which opens the exhaust orifice to the extent that the other orifice is closed, and vice versa.
14. A blow pipe having orifices through which gas and air pass to the combustion point, and an exhaust orifice, in combination with means for simultaneously controlling said orifices to increase or decrease gas and air flow in synchronism and to maintain substantially uniform air pressure in the instrument.
15. A blow pipe having orifices through which gas and air pass to the combustion point, and an exhaust orifice, in combination with means comprising a single controllable element for simultaneously controlling said orifices to increase or decrease gas and air flow in synchronism and to maintain substantially uniform air pressure in the instrument.
16. A blow pipe having orifices through which gas and air pass to the combustion

- point and an exhaust orifice, in combination with means comprising a single valve for simultaneously controlling said orifices to increase or decrease gas and air flow in 5 synchronism and to maintain substantially uniform air pressure in the instrument.
17. A blow pipe having orifices through which gas and air pass to the combustion point, and an exhaust orifice, in combination 10 with means for simultaneously controlling said orifices to increase or decrease gas and air flow in synchronism and to maintain substantially uniform air pressure in the instrument in proportions variable at will.
- 15 18. A blow pipe having orifices through which gas and air pass to the combustion point, and an exhaust orifice, in combination with means comprising a single controllable element for simultaneously controlling said 20 orifices to increase or decrease gas and air flow in synchronism, and to maintain substantially uniform air pressure in the instrument in proportions variable at will.
19. A blow pipe comprising, in combination, air receiving and delivery pipes, a 25 valve chamber having inlet, outlet and exhaust ports, and a valve in said chamber having a duct to connect said ports; said ports and duct being formed so that the movement of the valve in one direction increases the flow of air to the delivery pipe and proportionately diminishes flow through the exhaust port, and vice versa.
20. A blow pipe comprising, in combination, air receiving and delivery pipes, a 30 valve chamber having inlet, outlet and exhaust ports, and a valve slidably arranged in said chamber having a duct which extends across said inlet port and has tapered 35 extremities adapted to intersect said outlet and exhaust ports, respectively.
21. In a blow pipe, the combination of 40 gas and air receiving and delivery pipes, a valve chamber and a valve movable longitudinally and rotatable in said chamber; said chamber and pipes being formed with 45 gas inlet and outlet ports and air inlet and outlet ports and the chamber with an exhaust port, and said valve with gas and air ducts arranged so that the movements of the 50 valve longitudinally and rotationally control the flow of gas and air to the combustion point in variable proportions and synchronously therewith control the outflow of air through the exhaust port so as to maintain substantially uniform pressure in the instrument.
22. In a blow pipe, the combination of 55 gas and air receiving and delivery pipes, a valve chamber having gas inlet and outlet ports communicating with said gas receiving and delivery pipes, respectively, air inlet and outlet ports communicating with said air receiving and delivery pipe, respectively, and an exhaust port on the opposite 60 side of the air inlet port from the air outlet port, and a valve slidably and rotatably arranged in said chamber formed with a gas duct crossing the gas inlet port which has a tapered extremity adapted to intersect the 65 gas outlet port and formed with an air duct extending across said air inlet port having tapered extremities, one of which is adapted to intersect the air outlet port, the other the exhaust port; the gas outlet port being conformed so that the rotation of the valve does 70 not change the effective size of the orifice between the gas duct and said port, while said air outlet and exhaust ports are conformed so that the rotation of the valve in 75 one direction diminishes the effective size of the orifice between the air duct and the air outlet proportionately increasing the effective size of the orifice between said air duct and the exhaust ports, and vice versa.
23. A blow pipe having a line for supplying air under pressure thereto, means for varying the supply of air to the combustion point and means for preventing the accumulation of back pressure in the air supply 80 line when the supply of air to the combustion point is decreased.

CLAYTON LAING.
